UNITED STATES PATENT OFFICE.

CHARLES TREGONING, OF LEAD CITY, DAKOTA TERRITORY.

CAR-BRAKE.

SPECIFICATION forming part of Letters Patent No. 293,823, dated February 19, 1884.

Application filed December 31, 1883. (No model.)

To all whom it may concern:

Be it known that I, CHARLES TREGONING, a citizen of the United States, residing at Lead City, in the county of Lawrence, Dakota Territory, have invented certain new and useful Improvements in Car-Brakes, of which the following is a description.

This invention relates to that class of car-brakes which are designed to be applied by the act of slackening the speed of the engine. A brake upon the cars which will be applied by the act of slackening the speed of the engine, when the train is in motion, would also be applied by an attempt to back the engine.

The object of my invention is, first, to apply the brakes automatically to a train of cars when in motion by the act of slackening the speed of the engine; and, second, to automatically remove the brakes thus applied when the engine exerts sufficient pressure to back the cars.

To this end my invention consists in the construction and combination of parts forming a car-brake and its connections, herein-after described and claimed, reference being had to the accompanying drawings, in which—

Figure 1 is a side elevation, part in section, of a portion of a car, showing my automatic brake. Fig. 2 is an inverted plan view of the same, and Fig. 3 is a transverse vertical section at *x x* of Fig. 1.

A represents the car, having any usual trucks and wheels, and the common brakes *B*, which are operated, as usual, by the hand-wheel and axle *C* winding the chain *D*, which is attached to the connecting-rod *E*. This rod *E* is attached at one end to a lever-arm of the brakes, which are operated thereby to bind upon the wheels, as usual. The other end of rod *E* projects forward of its point of attachment to the chain *D*, and is formed into a hook, *f*, at its forward end, or rear end, if the brake in question is at the rear end of the car. At this point the characteristics of my invention begin.

F is a lever engaging the hook *f*, and pivoted upon a bolt, *a*, fixed in another lever, *G*, which is pivoted upon a bolt, *b*, to the body of the car.

H is the common draw-head of the car, provided with a stiff spring, *c*, which acts to

thrust the draw-head forward to ease the cars from a shock in coming suddenly together. To this common draw-head, which may be that of a car already in use, I attach a downward projection, *I*, having a hole in it to carry the forward portion of my actuating-rod *J*, which may reciprocate longitudinally therein. This rod *J* is provided at its outer end with a large bumper-head, *d*, and is set to project forward of the draw-head to meet the head of a similar rod on the next car, and along its body from its inner end it is screw-threaded for longitudinal adjustment in a stud, *K*, which is fixed to rotate slightly in lever *F*. This screw-rod may have a check-nut, *e*, to bind it from jarring loose by impinging against stud *K*.

L is a spring acting between an abutment, *M*, and the rod *J*, of sufficient strength to push the rod *J* and the adjacent end of lever *F* forward when they are free to be so moved, but not strong enough to hold out the rod *J*, so that the car might be backed thereby, and not near so strong as the spring *c* of the draw-head.

N is a stud or bolt projecting from the draw-head to engage lever *G* by entering a hole which is elongated longitudinally therein to compensate for the variation between the straight-line movement of the draw-head and the circular movement of stud *N* around pivot *b*. The hole in lever *F* for pivot *a* is also elongated for a similar purpose.

As a forward motion of hook *f* applies the brake, and as lever *F* engages hook *f* only at its rear side, said hook is free at all times to be drawn forward by the usual hand-wheel, so that my automatic attachment does not prevent the use in the old way of the same brakes to which it is applied. The engine may be provided with a bumper, to meet the head of rod *J*, on the forward end of the foremost car. In that case the operation of braking up a train is as follows: The engineer slackens the speed of the engine, and if there is any momentum in the train which requires to be checked it pushes first the rod *J* of the forward car against the engine-bumper, thereby applying the forward brake and checking the speed of that car, so that the next car pushes in its own forward rod, *J*, and the rear rod of

the forward car, thus checking itself and further checking the forward car, so each succeeding car is checked, and that in direct ratio to its momentum, which is exactly the object to be attained. If there were no such brake-bumper on the engine, or if there were cars in the train not having my automatic brake appliances, then the next car to the rear in each case having my brakes would not be automatically braked; but the brakes might be applied to them by hand, as in the old style. Nevertheless, in such mixed trains, wherever two cars having my brakes were attached together, there my automatic brake would be applied by checking the speed of the forward of the two cars, as before described. If it were necessary to check the speed of a train going down a grade, it is only necessary to slacken the speed of the engine, when each car will apply its own brake just in proportion to the resistance offered by the engine to its momentum. Thus the engine, instead of having to resist the actual momentum of the whole train with its load, has only to offer sufficient resistance to push on the brakes and make the momentum of each car check itself. If it is desired to leave the cars with the brakes on, it is only necessary to tighten and fasten the hand-brake to the end cars after all the brakes have been automatically set. Then the engine may be detached, and the cars will remain with all the brakes set on, because the end cars prevent the rods J from pushing out. If the train were stopped on a grade, only the car at the foot of the train would have to be hand-braked to hold all the rest. If a train were to break loose from its engine and start downgrade, the rear guard, now at the head of the train, by applying the brake on the car now foremost, will, by checking it, apply the automatic brakes to the whole train, and quickly have it under control. Thus my automatic brake is independent of the engine.

Now, suppose that the engine starts to back. First, the brakes will be applied to the first car. Then, as the engine continues to back, the rods J will be pushed in, so that the draw-heads meet and are pushed in. The instant the draw-head begins to recede it carries with it lever G, the pivot a, and the lever F thereon, thereby disengaging lever F from hook f and releasing the brake, so that the same backing movement which at first applies the brakes will, when continued, finally release them, leaving the train free to back. Then, when the engine slackens its speed in backing, the draw-heads, by their strong springs, will be at first pushed out, reapplying the brakes, the rods J being already depressed, thus again stopping the train by checking the driving-power. Then if the engine be reversed the cars

will one after another be sufficiently separated to allow the rods J to project. Then the brakes will be released.

The advantages to be derived from thus placing the brakes of a whole train under control of the engineer or of one brakeman, and yet of being able to automatically remove the brakes by the act of backing, are too evident to need amplifying.

There are different ways in which the levers F and G may be pivoted to accomplish the same purpose, and it would be possible to do away with the lever G entirely by placing the pivot-bolt a of lever F in an arm rigidly secured to the draw-head.

The hook f might be substituted by a loop or other connection that would permit the rod to move ahead of the lever F, and yet to be moved ahead thereby.

The buffer-rod J might as well be suspended from the car as from the draw-head; but the buffer-rod heads should be central in the width of the cars, in order to meet each other.

What I claim as my invention, and wish to secure by Letters Patent, is—

1. The combination, with a car-brake having a hooked rod or its equivalent, forming part of the connection between the brake-lever and the brake-operating handle, a draw-head, and a spring therefor, of a buffer-rod hung to project beyond the draw-head, and a lever or levers connecting said buffer-rod with the aforesaid hooked rod, and having a pivotal connection with the draw-head, substantially as shown and described, whereby an inward movement of the buffer-rod will apply the brake, and an inward movement of the draw-head will release the brake, as specified.

2. The combination, with the hooked rod E, the draw-head H, having a pivot, a, attached to it, and the spring c, to force the draw-head outward, of the lever G, having a fixed pivot, b, and engaged by the pivot a, the lever F, pivoted to lever G, to engage the hooked rod E, the actuating-rod J, pivoted to lever F, and the spring L, substantially as and for the purpose specified.

3. The combination, with the draw-head H and the spring c, of the brake-actuating rod J, connected by levers and pivots with said draw-head and with the car-brake, said rod J being provided with a screw-thread, and a spring whereby the draw-head may be pushed out, and the actuating-rod may be still farther pushed out and may be adjusted relatively to the draw-head, as shown and described.
